Attorney

UNITED STATES PATENT OFFICE.

JOHN L. HOOD, OF PAWTUCKET, RHODE ISLAND.

PILFERPROOF BOX.

Application filed October 17, 1923. Serial No. 669,174.

To all whom it may concern:

Be it known that I, JOHN L. HOOD, a citizen of the United States, residing at Pawtucket, in the county of Providence and 5 State of Rhode Island, have invented new and useful Improvements in Pilferproof Boxes, of which the following is a specification.

This invention relates to certain new and 10 useful improvements in pilfer-proof boxes and pertains more especially to boxes of the type used in shipping goods by freight, express or parcel post.

The primary object of the invention is 15 to provide a novel box of this type wherein it is practically impossible to remove one or more of the boards or strips or a wall of the box, to obtain access to the contents, without rendering it instantly apparent that 20 the box has been tampered with.

A further object of the invention is to provide a box of this type which is of simple, economical and strong construction, and one wherein the fastenings, are securely held 25 in position and practically protected against removal except by breaking down the structure.

Still further and other objects will be later set forth and manifested in the course 30 of the following description.

In the drawings:—

Figure 1, is a perspective view of a box constructed in accordance with the present invention;

Figure 2 is a section on line 2—2 of Figure 1,

Figure 3 is a section on line 3—3 of Figure 1,

Figure 4 is a section on line 4—4 of Figure 1,

Figure 5 is a detail perspective view of one of the metal strips employed in constructing the box, and

Figure 6 is a like view of another of the metal strips.

In proceeding in accordance with the present invention, the box is preferably constructed of wood pieces or strips or wood boards to form the end and side walls, as 50 well as the top and bottom of the box.

The end walls are formed of strips 1 which are of greater thickness than the remaining strips and are provided with tongues 2, which latter may be formed by 55 saw-cuts of kerfs 3 on one side thereof, the kerfs being spaced from the outer side faces

of the strips. The opposite sides of the tongues, formed by cutting away the opposite sides of the strips, provide the shoulders 4, while the outer ends of the tongues 60 are spaced inwardly from the outer ends of the strips. Substantially J-shaped angle irons engage over the tongue and have wide sides 6 engaging in the kerfs 3, intermediate walls 7 engaged over the tongue ends and 65 narrow sides 8, the latter engaging the inner side faces of the tongues and being disposed at a relative considerable distance outwardly of the shoulders 4.

The side walls are composed of wood 70 strips 9 the ends of which are provided with saw-cuts or kerfs 10 to receive the flat metal strips 11, which latter are located closer to the outer faces than to the inner faces of 75 the strips 9.

The top wall is composed of wood strips 12, the outer ends of which have saw-cuts or kerfs to receive the flat metal strips 13, while the bottom wall is composed of wood strips 14 the ends of which have saw-cuts or 80 kerfs to receive the flat metal strips 15.

The angular and flat strips are first secured to the various walls of the box, preferably having a tight frictional or driving fit into the kerfs thereof so as to hold the 85 various boards, of which the walls are formed, in assembled relation. Brads 22 are employed to initially hold the angular strips in place. The side walls are first connected to the end walls by driving headless 90 screw nails 16 through the metal strips 11 and into the boards 1 constituting the end walls.

The upper and lower edges of the side walls are nailed to lie substantially flush 95 with the shoulders 4, as shown in Figure 2.

The top and bottom are then nailed in position by similar nails 17 driven through the flat metal strips 13 and 15 thereof, as shown in Figure 3. Similar nails 18 are 100 then driven through the wide sides 6 of the angular metal strips and into the top and bottom walls, the nails as shown in Figure 2, extending beyond the narrow sides 8 of the angular strips. 105

As shown in Figure 2 of the drawings, the top and bottom walls 12 and 14 seat on the shoulders 4 so that should the boards shrink, the shoulders will prevent access to 110 the box interior.

The top and bottom walls are thus secured in position not only by the vertical nails

at their sides, but also by the horizontal nails 18' at their ends. Similarly, the side walls are secured by the vertical nails 17' and the horizontal nails 16', while the end walls are held in place by the horizontal nails 16' and the horizontal nails 18'.

As illustrated in Figures 2, 3 and 4 the nails are driven to have their screw or roughened ends 16, 17 and 18 extend on the inner sides of the metal strips. It will thus be seen that the metal strips protect the nails since they prevent access to the same to allow the removal or extraction thereof.

Obviously, different forms of headless nails may be used, for example ones having roughened, instead of screw, peripheries.

It will thus be apparent that each of the nails is protected by a metal strip, the latter also holding the boards in position, presenting a strong structure which is practically proof against abstraction of its contents without same being instantly obvious.

Having thus described my invention, what I claim as new and desire to secure by Letters Patent is:

1. In a box, ends composed of boards having end tongues with kerfs on the outer sides of the tongues and shoulders adjacent to the inner sides thereof, J-shaped metal plates engaged over the tongues and in the kerfs, sides, a top and a bottom each composed of boards having end kerfs located closer to the outer than to the inner faces of the last named boards, metal plates in the last named kerfs, the sides being arranged to lie between and flush with the respective shoulders of the ends, the top and bottom being seated on the shoulders and on the side edges of the sides, and headless roughened fastenings driven through the wide sides of the J-shaped plates and into the ends of the top and bottom, through the top and bottom and into the sides and through the sides into the ends, all of the fastenings having their roughened parts extending on the inner sides of the respective metal plates.

2. In a pilfer-proof box, ends having top and bottom shoulders, angle irons embedded in the end edges of the ends, a top and a bottom seated on the respective shoulders, sides between the top and bottom, metal strips embedded in the end edges of the sides, and in the side edges of the top and bottom, and headless roughened fastenings driven through the walls to connect same

and having their roughened parts disposed on the inner faces of the respective strips.

3. In a box, ends having top and bottom tongues with kerfs on the outer sides of the tongues and shoulders adjacent to the inner sides thereof, J-shaped metal plates engaged over the tongues and in the kerfs, a top and a bottom seated on the shoulders, sides engaged with the ends and top and bottom, and headless fasteners driven through the wide sides of the J-shaped plates and into the ends of the top and bottom.

4. In a box, ends having J-shaped metal plates embedded in the top and bottom edges thereof, a top and a bottom having metal plates embedded in the side edges thereof, sides having metal plates embedded in the end edges thereof, headless fasteners driven through the wide sides of the J-shaped plates and into the ends of the top and bottom, and headless fasteners driven through the second named metal plates of the sides, top and bottom to connect the sides to the ends and the top and bottom to the sides.

5. In a box, ends having top and bottom tongues and shoulders at the inner sides of the tongues, metal plates embedded in the tongues, a top and a bottom seated on the respective shoulders, metal plates embedded in the side edges of the top and bottom, sides engaged with the ends and disposed between the top and bottom, metal plates embedded in the ends of the sides, headless fasteners extending through the metal plates of the ends and into the ends of the top and bottom, headless fasteners extending through the metal plates of the sides and into the ends, and headless fasteners extending through the top and bottom and into the sides.

6. In a box, ends having J-shaped metal plates, embedded in their top and bottom edges so as to be carried wholly by said ends, a top and a bottom engaged with the ends, sides connected to the top and bottom and to the ends, and headless fasteners extending through the wide sides of the J-shaped metal sides of the said plates and into the top and bottom.

In testimony whereof I have signed my name to this specification in the presence of two subscribing witnesses.

JOHN L. HOOD.
